DRUM ARRANGEMENT FOR A MOISTURE EXTRACTING PRESS

Josef Willmes, Nibelungenstr. 58, Bensheim an der Bergstrasse, Germany

Filed Jan. 31, 1961, Ser. No. 66,185

Claims priority, application Germany Feb. 12, 1960
17 Claims. (Cl. 100—107)

The present invention relates to presses for extracting moisture from a moisture-containing material, and more particularly to an improved drum arrangement for such presses.

In a type of press with the improvement of which this invention is more specifically concerned, a moisture-containing material is compressed in a drum consisting essentially of a tubular member of circular or angular cross section. A platen member is axially movable in the tubular member and a second platen member may be either fixed or also axially movable. The drum cavity is thus radially contained in the tubular member and axially defined by the two platen members. At least a portion of the drum walls is perforated to permit liquid to escape when a moisture-containing material is compressed between the platens when they move toward each other.

It is an important object of the invention to expedite the moisture removal from a material being compressed between the platen members of a press of the type described.

Another object is an improvement in the removal of the dry residue remaining in the drum after pressing.

A more specific object of the invention is the provision of simply and automatically established drainage channels in the cake of material being compressed in the drum, the cake being divided by the channels into a plurality of layers which are serially arranged in the direction of applied pressure.

Yet another object of the invention is the provision of simple and automatically effective means for breaking the extracted cake into small fragments prior to discharge from the press drum, or prior to a secondary pressing.

A further object is the retention in the drum of the dry constituents of the material being compressed and the prevention of the dry constituents being admixed with the extracted liquid.

Other objects and many of the attendant advantages of this invention will be readily appreciated as the same becomes better understood by reference to the following detailed description when considered in connection with the accompanying drawing in which like reference numerals designate like parts throughout the figures thereof, and wherein:

FIG. 1 shows a cylindrical press drum equipped with a preferred embodiment of the invention in side elevational axial section;

FIG. 2 shows the drum of FIG. 1 in front elevational radial section;

FIG. 3 illustrates a cylindrical drum substantially similar to that of FIG. 1, but provided with a modified embodiment of the invention;

FIG. 4 shows an additional modified embodiment of the invention in a view corresponding to that of FIG. 3;

FIG. 5 is a front elevational sectional view of a press drum of square cross section provided with yet another modified embodiment of the invention;

FIG. 6 shows a further embodiment of the invention as applied to a drum of rectangular cross section which is shown in side-elevational axial section;

FIG. 7 illustrates a modification of the apparatus of FIG. 6;

2

FIG. 8 shows a perspective view of a detail of the devices of FIGS. 1-3 and 5-7 on a greatly enlarged scale;

FIG. 9 shows a modification of the detail of FIG. 8; FIG. 10 is a fragmentary axially sectional view of a drum equipped with yet another preferred embodiment of the invention, the scale of the view being substantially greater than that of FIGS. 1-7;

FIG. 11 shows the device of FIG. 10 in plan view in a radial plane, partly in section, the scale of FIG. 11 being somewhat smaller than that of FIG. 10;

FIG. 12 is a somewhat diagrammatic radially sectional view of the drum of FIG. 10 on a reduced scale;

FIG. 13 illustrates a modification of a detail of the device of FIG. 10 in perspective view;

FIG. 14 is an elevational view of a locking element of the device of FIG. 13 in the open condition;

FIG. 15 shows the element of FIG. 14 in the closed condition; and

FIG. 16 illustrates the device of FIG. 10, as modified by the detail of FIG. 13, the view corresponding to that of FIG. 10.

Referring now to the drawing, and initially to FIG. 1, there is seen the drum of a press of the type disclosed in more detail in the copending application of Oskar Braun,

Serial Number 768,986, filed October 22, 1958, now United States Patent No. 2,986,082. The press drum has a fixed platen member or bottom 1 from which staves

2 extend in an axial direction. The staves are held together by steel hoops 3 which are axially connected by reinforcing bars 4. The staves 2 jointly form a tube, one axial end of which is closed by the fixed platen member 1.

The other axial end of the drum cavity is defined by a movable bottom or platen member 5. Referring now to the drawing, and initially to FIG. 1, there is seen the drum of a press of the type disclosed in more detail in the copending application of Oskar Braun, Serial Number 768,986, filed October 22, 1958, now United States Patent No. 2,986,082. The press drum has a fixed platen member or bottom 1 from which staves 2 extend in an axial direction. The staves are held together by steel hoops 3 which are axially connected by reinforcing bars 4. The staves 2 jointly form a tube, one axial end of which is closed by the fixed platen member 1. The other axial end of the drum cavity is defined by a movable bottom or platen member 5.

The free ends of the staves 2 are connected by a spider-shaped hub member 6 which is freely rotatable on a bearing face 8 of an internally threaded member 7. Rotation of the hub member 6 on the bearing face 8 is facilitated by the interposition of a thrust ball bearing 9 which absorbs axial stresses. A threaded spindle 10 which engages the internal threads of the member 7 is fixedly fastened to the center of the platen member 5.

The fixed platen member 1 is provided with a trunnion 11 which is journaled in a bearing 12 which is an element of the press frame which is not shown in full since it is in itself not a necessary part of this invention. The internally threaded member 7 is secured on the frame against rotation. When the spindle 10 rotates in the member 7, the movable platen member 5 moves axially toward or away from the fixed bottom 1. As illustrated in FIG. 1, the movable bottom 5 is in the terminal position of its movement outward of the drum cavity and away from the fixed bottom 1.

Wide ribbons 14 extend between the two platen members 1 and 5. Their length is approximately equal to the maximum spacing between the two platen members so that they are tensioned in the position of the movable platen member illustrated in FIG. 1. As better seen in the radially sectional view of FIG. 2, the ribbons when in the tensioned condition extend mainly in planes parallel to each other and to the axis of the drum.

It will be understood that the walls of the drum are provided with relatively small apertures to permit escape of liquid separated from the dry constituents of the material being compressed between the platen members 1 and 5. In a drum the axial wall of which is composed of staves, these apertures are most conveniently provided by slightly spacing the staves, from each other along the circumference of the drum. The apertures thus formed are too small to be visible on the scale of FIGS. 1 and 2. The drum is equipped with a door 2' in its cylindrical

wall for loading of material to be extracted, and for removal of dry residue.

The ribbons 14 consist preferably of woven or braided fibrous material which is readily wetted by the liquid constituent of the material that is to be extracted in the press. The fibers of the ribbon materials should show capillary positive activity relative to the liquid to be extracted, that is, they should enhance the capillary flow of the liquid along the fibers. In the most common case of water or an aqueous liquid being separated from a dry residue, virtually all fibers that can be woven or combined into non-woven materials, including natural textile materials such as cotton, wool, or hemp; synthetic organic fibers such as those of cellulose esters and ethers, polyamides, vinyl chloride and vinylidene chloride polymers; and inorganic synthetic or natural fibers such as those of glass or metals are suitable ribbon materials.

Additional ribbons 13, wider than the ribbons 14 are placed along the internal face of the cylindrical drum wall in such a manner that they overlap each other along axial lines. The ribbons 14 arranged in the cavity of the drum shown in FIGS. 1 and 2 provide flow channels for the liquid constituent to be extracted and prevent escape of solid particles from the drum. These channels extend axially of the drum from one bottom to the other. Additional passages are provided by the ribbons 13 along the radially defining cavity walls. The ribbons 13 are preferably arranged in such a manner that they make contact with the ribbons 14 either in the tensioned condition of the latter (not shown) or when the movable bottom 5 approaches the fixed bottom 1 whereby the tension in the ribbons 14 is relaxed and they are deflected by the materials compressed as will be presently discussed in more detail.

The apparatus described so far operates as follows:

With the drum in the position shown in FIG. 2 and the bottoms 1 and 5 as far removed from each other as the length of the ribbons 14 permits, the door 2' of the drum is opened. The ribbons 14 directly underlying the door 2' are at first spread apart or pushed aside to facilitate loading. When the drum is partly filled with the material to be extracted, the top ribbons may be relaxed to resume their normal axial position, and charging of the drum is completed. The door is then closed.

The closed drum is rotated and the movable bottom 5 is gradually advanced in a direction inward of the drum cavity. The ribbons 14 which are embedded in the gradually thickening cake of extracted material assume a meandering shape under the pressure exerted by the contracting cake which is no longer effectively counteracted by axial tension. The loops or folds formed by the ribbons 14 spread transversely of the drum axis as the platen member 5 advances. In an early phase of the extraction process the cake of material is axially subdivided into flat axial portions by almost continuous radial sheets of fibrous tissue constituted by combined elements of the several ribbons.

The effective surface areas of the cake through which liquid may pass outward is thus not only determined by the perforate rigid walls of the drum but also by the interface of the cake and the ribbons. The liquid can travel in the fibrous capillary active ribbon material axially of the drum, but also transversely of the drum axis. When the movable platen member 5 has performed only a fraction of its stroke, the ribbons 14 make contact with the ribbons 13 along the cylindrical drum wall and establish a continuous system of channels which discharges liquid through the apertures between the staves 2. The ribbons 14 accelerate the liquid discharge by substituting a flow path through the relatively permeable ribbon material for a flow path through the extracted material which becomes progressively less permeable as the cake is compacted.

When the cake in the drum has been compressed to the desired extent, the movement of the spindle 10 is

reversed and the movable bottom 5 is made to travel outward of the drum cavity while rotation of the drum continues. The ribbons 14 are thereby straightened and release the portions of the cake which were held between their folds. The cake portions drop to the bottom of the gradually enlarged drum cavity. Since the drum is simultaneously rotated, the cake portions are further comminuted by the resulting tumbling action.

The comminuted cake may then be compressed again to yield residually retained liquid. For re-pressing, the direction of rotation of the spindle 10 is simply reversed. Although the drum is no longer full and the ribbons 14 are not as effectively embedded in the material to be extracted as was the case originally, continued rotation of the drum causes the partly extracted material to be distributed between the ribbons in such a manner that the capillary activity of the ribbon material is used to advantage.

After the final pressing step, the door 2' is opened and the substantially dry and broken cake is discharged by merely rotating the drum with the door removed or in the open position.

The other embodiments of the invention illustrated in FIGS. 3 to 15 operate in substantially the same manner. They differ from the apparatus of FIG. 1 in additional features or in modified details intended to meet specific operating conditions.

In the apparatus seen in radial cross section in FIG. 3, a drum of substantially the same type as shown in FIGS. 1 and 2 is equipped with ribbons 15 arranged in radial planes offset by equal angles about the axis of the drum. This arrangement is somewhat less convenient when filling the drum with a material of high viscosity but it provides capillary flow channels of minimum average length for the liquid to be extracted, and is thus preferred for materials high in liquid content and therefore generally of relatively low viscosity.

The ribbons are replaced by a large number of closely spaced fibrous ropes 16 in the apparatus of FIG. 3 which is preferred for handling materials of high viscosity forming strongly cohering cakes. It is essential that the number of ropes be high enough that the ropes may form a network substantially equal in capillary capacity to the ribbons 14 of FIGS. 1, 2, or 3. The spacing of the ropes must be so close that the ropes should touch each other and the ribbons 13 provided along the cylindrical wall of the drum cavity at an early stage of the pressing operation. The ropes are particularly effective in breaking up a strong cake. The large number of ropes again aids in subdividing the cake and thus facilitates its further comminution.

A preferred arrangement of ribbons 19 in a drum 17 of square or otherwise rectangular section is shown in FIG. 5 in a view taken transversely of the drum axis. The four walls of the drum 17 are made of perforated boards one of which is removable to provide access to the drum cavity. To facilitate charging, the ribbons mainly extend in planes parallel to the drum axis and at right angles to the removable drum wall, thus giving convenient access to the compartments formed between the ribbons 19.

When the material in the drum 17 is axially compressed by an arrangement corresponding to the bottoms 1 and 5 in FIG. 1, the ribbons 19 are deflected toward planes transverse of the drum axis, thus subdividing the charge in the drum not only in a direction transverse of the axis, as provided by the original compartments between the ribbons 19, but also in the direction of the compressive stresses applied. The ribbons extend over the full length of the drum, and also from wall to wall in a transverse direction. They thus provide flow paths for the liquid being extracted and accelerate its discharge through the perforations 18 in the walls of the drum 17. It will be appreciated that the drum 17 may be equipped with additional layers of fibrous material along the walls

of the drum in the manner represented by the ribbons 13 in FIGS. 2, 3, and 4.

FIG. 6 shows another drum arrangement of the invention in side elevational axial section. The drum 17 itself is of square cross section as shown in FIG. 5. It is equipped with a fixed bottom 20 and a movable bottom 21 which may be moved toward and away from the fixed bottom in any desired manner, for example, by an arrangement analogous to that of FIG. 1. Two ribbons 22 extend axially between the two drum bottoms or platen members 20, 21 respectively adjacent two opposite side walls of the drum 17. A large number of axially spaced transverse ribbons 23 connects the axial ribbons 22. In the position illustrated, the weight of the transverse ribbons 23 slightly deflects the axial ribbons 22 from a straight axial run which they would assume under the tension exerted by the platen members 20 and 21, but upon rotation of the drum 17 about its axis this deviation will disappear. For charging, the drum 17 of FIG. 6 is rotated through 90° from the position seen in FIG. 6 so that the several compartments formed between adjacent ones of the ribbons 23 present their open tops for filling.

When the platen member 21 is moved toward the fixed platen member 20, the axial ribbons 22 are placed at least in part adjacent the perforations (not shown) in the walls of the drum 17 and act as manifolds drawing liquid from the ribbons 23.

Charging and emptying of a press drum may be difficult in the presence of the pliable elongated ribbons or ropes with some materials, either because of the viscosity of the starting material, or because of tackiness of the final cake which tends to adhere to the fibrous surfaces. The embodiment of the invention shown in FIG. 7 illustrates a device for overcoming such difficulties.

The drum 24 of FIG. 7 is seen in side elevational axial section. It is of square cross section and equipped with one removable side wall. It is equipped with a fixed bottom 25 and a movable bottom 26. The bottoms each have two integral rails projecting toward the other bottom and formed with opposite grooves 25', 26' longitudinally extending in a direction away from the open side of the drum 24. Two carrier plates 27 approximately coextensive with the bottoms 25, 26 are slidably inserted in the grooves 25', 26' and held in place by the removable side wall (not shown). A system of axial ribbons 28 and transverse ribbons 29 substantially identical with the ribbon system of the embodiment shown in FIG. 6 is fastened to the two carrier plates 27 and thus removable by sliding the plates out of the grooves 25', 26' during the charging and/or during the emptying of the drum 24.

FIG. 8 shows means for removing the entire ribbon system of the drum 17 in FIG. 6 without the use of carrier plates. The end of the woven ribbon 22 is shown in a greatly enlarged perspective view. The end portion of the ribbon is folded over to form a loop 22' which is secured by a row of stitches. A rod 30 passes transversely through the loop 22'. It centrally carries an eye 31 which extends axially outward through an opening in the edge of the loop 22' and engages a hook 32 fixedly fastened to the bottom 20 of the drum 17.

The arrangement illustrated in FIG. 8 permits removal of the ribbon system shown in FIG. 6 by separating the elements of only four hook-and-eye fasteners 31, 32, but it is also possible to release the ribbon system from one fastener only to facilitate charging of the drum.

It is evident that the fastener arrangement of FIG. 8 can readily be applied to the ribbon arrangements of FIGS. 1 to 3 and 5 to make individual ribbons readily removable, and that it can be modified to accommodate the ropes of the embodiment shown in FIG. 4 although different fastening means for ropes are preferred and will presently be described.

A modification of the hook-and-eye arrangement of

FIG. 8 is shown in FIG. 9. The hook 32 is replaced by a threaded stud 34 fixedly fastened to and axially projecting from a bottom of the drum (not shown). It engages an eye 33 on the rod 30 the opening of which is only slightly larger than the diameter of the stud 34. A wing nut 35 on the stud 34 secures the end of the ribbon 22 to the drum somewhat more securely than the open hook-and-eye arrangement of FIG. 8 at some slight sacrifice in the ease of engagement and disengagement of the ribbons.

FIG. 10 shows a modified arrangement for securing rope type pliable members to the bottom 36 of a drum. The axially sectional view of FIG. 10 is supplemented by a plan view of a portion of the bottom in FIG. 11, and by a somewhat diagrammatic radially sectional view of the drum of FIG. 10 on a reduced scale.

The fixed bottom 36 of the drum of which only a portion of a perforated side wall 38 is otherwise shown has a carrier plate fastened thereto by countersunk bolts 37. The carrier plate consists of four identical and interchangeable segments 37 each of which is spaced from the bottom 36 by a plurality of integral axial projections 39 so as to provide a hollow drainage space 40 between the segments 37 and the fixed bottom 36. This drainage space is axially aligned with a circumferential row of relatively large perforations in the side wall 38.

Openings 41 in the segments 37 provide passages between the main drum cavity and the drainage space 40. A rope 42 passes through each opening 41. The ropes are each composed of several strands of a continuous length of a string, narrow ribbon or the like which is skeined to form several flattened loops. The bight portions 43 of the loops pass through the openings 41 and are prevented from slipping out of the space 40 by a locking rod 44 which extends transversely of the rope axis.

The straight rods 44 may be replaced to advantage by elongated open rings 45 of the type shown in perspective view in FIG. 13. The ring has an open slot 46 wide enough to permit passage of an individual strand of string or ribbon which composes the rope 42, but too narrow to permit the simultaneous passage of more than one strand. Alternatively, there may be employed a ring 47 of the type shown in FIGS. 14 and 15 which originally has two free ends 47' which extend in spaced parallel planes and thus provide a wide slot for engaging the bight portions 43 of a rope 42. When the rope is in place, the free ends 47' are bent from the position seen in FIG. 14 and in broken lines in FIG. 15 into a common plane as indicated in fully drawn lines in FIG. 15, thus substantially closing the gap. The use of the rings 45 in the drum of FIG. 10 is illustrated in FIG. 16.

The dimensions of the rings 45 or 47 are selected in such a manner that the rings with a rope 42 thereon may be passed through an opening 41 in the longitudinal direction, but cannot pass through the opening when transversely aligned. Such an arrangement makes insertion of individual ropes 42 into the segments 37 very easy.

It is preferred to combine several ropes 42 into a bundle by rings 49 arranged at least at two longitudinally spaced points of the bundle. The members of the bundle occupy minimum space and offer minimum interference to loading or unloading of the drum when the ropes 42 are tensioned. Yet, they spread and their individual members assume independent meandering shapes substantially without hindrance by the rings 49 to provide a network of drainage channels in the cake. A preferred pattern of bundles is diagrammatically indicated in FIG. 12 in which each circle indicates an opening 41 and a rope 42 passing through the opening, and the lines connecting adjacent circles are indicative of the connection of the corresponding ropes 42 by a ring 49 to form a bundle.

FIG. 12 also shows a peripheral row of individual ropes 42 which extend along the cylindrical side wall 38

to perform the functions of the ribbons 13 in the embodiment of FIG. 13.

When the drum of FIGS. 10 to 12 is to be loaded, the movable bottom which will be understood to be similarly provided with segments 37 as the fixed bottom 36, is positioned away from the fixed bottom 36 to tension the bundles of ropes 42. The door (not shown) in the side wall 38 is opened and the ropes 42 adjacent the door opening are pushed aside to facilitate entry of the material to be extracted. If the nature of the material so requires, the ropes 42 adjacent the door opening may also be equipped with hook-and-eye type fasteners as shown in FIGS. 8 and 9 so that they may be temporarily removed and reinstalled when loading is completed.

It may also be convenient to remove an entire segment 37 from each drum bottom by releasing the respective screws 37' together with the ropes 42 which extend between the segments, and to reinstall the segments when the drum is at least partly loaded. The division of the carrier plate into four segments as shown in FIG. 12 is not critical, and the plate may be divided in any other manner as specific operating conditions may warrant. It is preferred though that individual segments be identical to make them interchangeable, or that at least a majority of the segments be interchangeable. If an imperforate door is employed, the peripheral row of ropes 42 may be interrupted in the area adjacent the door since it would not serve its principal purpose of facilitating radial discharge of liquid, and the omission of ropes adjacent the door opening will facilitate loading.

When the drum is filled and the movable bottom moves toward the fixed bottom, or when two movable bottoms provided move toward each other, the axial shortening of the cake of material in the drum causes the ropes to assume individual meandering shapes in which the ropes intersect and form a system of communicating channels for the flow of the liquid being extracted, while simultaneously subdividing the cake into axially divided sections substantially in the same manner as the ribbons 14 of the press shown in FIG. 1. The relatively hard individual strands of the ropes maintain continuous flow channels for the liquid which lead to and terminate in the drainage space 40 so that a major portion of the liquid extracted leaves the drum through the large perforations of the side wall 38.

When pressing is completed, the bottoms of the drum are moved away from each other and the straightening ropes 42 break the cake formed into smaller particles in the manner described above in more detail.

The drum arrangements illustrated and described may be modified in many ways as will be apparent to those skilled in the art. If so desired, the bottoms may be perforated in the same manner as shown for the side walls in FIGS. 5 and 10. In that event, ribbons 13 or ropes corresponding to the peripheral row of ropes in FIG. 12 are preferably arranged along the bottom faces as well.

It will usually be most convenient to arrange the pliable fibrous members, such as the ribbons and ropes illustrated in such a manner that they will extend between the bottoms along straight lines parallel to the drum axis when in tension. Other arrangements however may be chosen without departing from the spirit and scope of the invention. When two segments 37 on one drum bottom are interchanged without a corresponding change on the other drum bottom, the ropes 42 shown in FIG. 10 will still extend along straight lines between the two drum bottoms, but the lines will no longer be parallel. Such a configuration of the ropes may be found convenient when charging relatively viscous material to the drum where temporary removal of ropes or groups of ropes is not desirable. The modified configuration of the ropes near the door opening may provide easier access to the drum cavity at some sacrifice in channelling efficiency during pressing.

The carrier plates may be provided with additional openings for passage of liquid therethrough, or some of the passages 41 seen in FIG. 10 may not be used for holding ropes 42 so as to provide free communication between an area of the drum cavity adjacent the carrier plate and the drainage space 40. A similar purpose may be served by covering the drum bottoms with a coarse screen in a manner well known in itself to provide a relatively wide open channel from the face of the bottom toward the perforations in the side wall.

While a specific type of press and its operation have been described, it will be appreciated that the invention is not limited to any specific press. It is equally applicable to vertically or horizontally operating presses, and the manner in which the platen members are moved toward and away from each other has no bearing on the operation of the invention. It is also not limited to the continuously rotating drum described for the purpose of the disclosure. Loading and unloading of the drum may be achieved otherwise than by gravity, and the opening or openings for admitting the material to be extracted, and for separately withdrawing the solid and liquid constituents of the material may be disposed at will.

These and other modifications are fully contemplated and may obviously be resorted to by those skilled in the art without departing from the spirit and scope of the invention as hereinafter defined by the appended claims, as only preferred embodiments of the invention have been disclosed.

What I claim is:

1. In a press drum arrangement, in combination, a tubular member having an axis and radially defining a cavity about said axis; two platen members in said tubular member, said platen members transversely extending of said axis and axially defining said cavity, at least one of said members being formed with apertures therethrough communicating with said cavity, and one of said platen members being axially movable toward and away from the other platen member between two terminal positions; and a plurality of pliable elongated flat ribbons of fibrous capillary active material each having two end portions respectively secured to said platen members said material being permeable to liquid and said pliable flat ribbons extending between said platen members along substantially straight lines when said one platen member is in one of said terminal positions thereof away from the other platen member.

2. In an arrangement as set forth in claim 1, said tubular member and said platen members constituting the wall of said cavity, at least a portion of said wall being covered with a layer of fibrous capillary material permeable to liquid, said layer being in contact with at least one of said ribbons.

3. In an arrangement as set forth in claim 2, said wall portion being a face portion of said tubular member in said cavity.

4. In an arrangement as set forth in claim 3, said layer including a plurality of partly overlapping ribbon shaped elements.

5. In an arrangement as set forth in claim 1, said ribbons defining respective axially extending parallel planes when said one platen member is in said one terminal position thereof.

6. In an arrangement as set forth in claim 1, said ribbons defining respective axially and radially extending planes converging toward said axis when said one platen member is in said one terminal position thereof.

7. In an arrangement as set forth in claim 1, a plurality of elongated foldable members each having two ends secured to respective ones of said ribbons and extending between said ends transversely of said axis.

8. In an arrangement as set forth in claim 1, said tubular member being of rectangular cross section so as to define four walls of said cavity, two of said pliable ribbons extending along two of said walls, opposite each

other, the remainder of said ribbons extending between said two ribbons in a direction substantially parallel to the other two walls of said cavity when said one platen member is in said one terminal position thereof.

9. In a press drum arrangement, in combination, a tubular member having an axis and radially defining a cavity about said axis; two platen members in said tubular member, said platen members transversely extending of said axis and axially defining said cavity, at least one of said members being formed with apertures therethrough communicating with said cavity, and one of said platen members being axially movable toward and away from the other platen member between two terminal positions; a fastening member releasably secured to one of said platen members; and a plurality of pliable elongated members of fibrous capillary active material each having two end portions respectively secured to said fastening member and to the other one of said platen members, said material being permeable to liquid, and said pliable members extending between said platen members along substantially straight lines when said one platen member is in one of said terminal positions thereof away from the other platen member.

10. In a press drum arrangement, in combination, a tubular member having an axis and radially defining a cavity about said axis; two platen members in said tubular member, said platen members transversely extending of said axis and axially defining said cavity, at least one of said members being formed with apertures therethrough communicating with said cavity, and one of said platen members being axially movable toward and away from the other platen member between two terminal positions; a plurality of pliable elongated members of fibrous capillary active material each having two end portions respectively secured to said platen members, said material being permeable to liquid and said pliable members extending between said platen members along substantially straight lines when said one platen member is in one of said terminal positions thereof away from the other platen member; and a plurality of hook-and-eye fastening means, each of said fastening means having two releasably engageable elements, one of said elements being mounted on one of said end portions of a pliable member, and the other element being mounted on one of said platen members and engageable with said one element for securing said end portion to said platen member.

11. In a press drum arrangement, in combination, a tubular member having an axis and radially defining a cavity about said axis; two platen members in said tubular member, said platen members transversely extending of said axis and axially defining said cavity, at least one of said members being formed with apertures therethrough communicating with said cavity, and one of said platen members being axially movable toward and away from the other platen member between two terminal positions; a plurality of pliable elongated ropes of fibrous capillary active material each having two end portions respectively secured to said platen members, said material being permeable to liquid and said ropes extending between said platen members along substantially straight lines when said one platen member is in one of said terminal positions thereof away from the other platen member; and means for securing a plurality of longitudinally spaced portions of one of said ropes to corresponding portions of another rope, whereby said ropes are combined into a bundle.

12. In a press drum arrangement, in combination, a tubular member having an axis and radially defining a cavity about said axis; two platen members in said tubular member, said platen members transversely extending of said axis and axially defining said cavity, at least one of said members being formed with apertures therethrough communicating with said cavity, and one of said platen

members being axially movable toward and away from the other platen member between two terminal positions; a plurality of pliable elongated ropes of fibrous capillary active material each having two end portions respectively secured to said platen members, said material being permeable to liquid and said ropes extending between said platen members along substantially straight lines when said one platen member is in one of said terminal positions thereof away from the other platen member; at least one of said ropes containing a continuous length of material folded to form a plurality of parallel strands, two of said strands being joined by an integral bight portion.

13. In an arrangement as set forth in claim 12, a fastening member on one of said platen members, said fastening member being formed with an opening, said bight portion passing through said opening and forming a loop adjacent said fastening member, and a locking member passing through said loop and abutting against said fastening member when said strands are longitudinally tensioned.

14. In a press drum arrangement, in combination, a tubular member having an axis and radially defining a cavity about said axis; two platen members in said tubular member, said platen members transversely extending of said axis and axially defining said cavity, at least one of said members being formed with apertures therethrough communicating with said cavity, and one of said platen members being axially movable toward and away from the other platen member between two terminal positions; a plurality of pliable elongated members of fibrous capillary active material each having two end portions respectively secured to said platen members, said material being permeable to liquid and said pliable members extending between said platen members along substantially straight lines when said one platen member is in one of said terminal positions thereof away from the other platen member; a plurality of fastening plates releasably mounted on a face of one of said platen members in said cavity, said fastening plates jointly being substantially coextensive with said face; and fastening means on said plates for securing said pliable members to said plates.

15. In an arrangement as set forth in claim 14, said fastening plates being of substantially identical shape.

16. In an arrangement as set forth in claim 14, at least one of said fastening plates being formed with perforations and having a plurality of axial projections abutting against the corresponding platen member, whereby a hollow space is formed between said fastening plate and said platen member, said perforations communicating with said cavity and said hollow space.

17. In an arrangement as set forth in claim 14, said fastening means including a plurality of fastening members arranged in a peripheral row about said axis adjacent said tubular member.
